CLAIM

The ornamental design for a pair of work vehicle headlights, as shown and described.

DESCRIPTION

FIG. 1 is a front elevational view of a pair of work vehicle headlights in accordance with our new design;

FIG. 2 is a left hand side perspective view of a left hand side work vehicle headlight illustrated in FIG. 1, which is a mirror image of a right hand side work vehicle headlight; and,

FIG. 3 is a front elevational view of the left hand side work vehicle headlight illustrated in FIG. 1.

The broken lines showing the work vehicle are provided for the purpose of illustrating environmental structure and form no part of the claimed design.

1 Claim, 3 Drawing Sheets
